UNITED STATES PATENT OFFICE

173,288

HOUSE TRAILER BODY

Eike Ukena, Monrovia, Calif., assignor to Pan-American Trailer Coach Co., Division of Mid-States Corp., Monrovia, Calif., a corporation of Illinois

Application October 8, 1953, Serial No. 27,121

Term of patent 14 years

(Cl. D14—3)

To all whom it may concern:

Be it known that I, Eike Ukena, a citizen of the United States, residing at 827 Oakglade Drive, city of Monrovia, county of Los Angeles, State of California, have invented a new, original, and ornamental Design for a House Trailer Body, of which the following is a specification, reference being had to the accompanying drawing, forming a part hereof.

Fig. 1 is a perspective view of a house trailer body showing my new design, and

Fig. 2 is another perspective view showing the opposite side, rear and top thereof.

The dominant feature of my design resides in the full line portion of the drawing.

I claim:

The ornamental design for a house trailer body, as shown and described.
